Attorney

UNITED STATES PATENT OFFICE

BIRDIE O. HORNER, OF COVINGTON, KENTUCKY

TRAY FOR HOSPITAL BEDS

Application filed July 30, 1930. Serial No. 471,780.

This invention appertains to attachments for beds and more particularly to a novel tray attachment for hospital beds.

One of the primary objects of my invention is the provision of novel means for associating a tray with a hospital bed, whereby a bed pan and urinal can be conveniently associated with the bed and instantly reached by the patient without necessitating awaiting of the arrival of a nurse.

Another important object of my invention is the provision of a novel support for the tray, whereby the tray can be readily swung to an inoperative position under the bed and to an operative position laterally of the bed, the tray having means within convenient reach of the patient whereby the tray can be swung to either one of its two positions.

A further object of my invention is the provision of a novel support for the tray embodying a clamp for engaging the bed rail, the clamp being of such a construction as to permit the quick and easy association thereof with said rail at the desired location and at the same time form an effective support for the swinging tray.

A still further object of my invention is to provide an improved urinal and bed pan tray for hospital beds of the above character, which will be durable and efficient in use, one that will be simple and easy to manufacture, and one which can be placed upon the market and associated with a hospital bed at a small cost.

With these and other objects in view, the invention consists in the novel construction, arrangement and formation of parts, as will be hereinafter more specifically described, claimed, and illustrated in the accompanying drawings, in which drawings:

Figure 1 is a top plan view of my improved tray attachment, showing the same attached to the bed rail of a hospital bed, illustrating the same in its inoperative position.

Figure 2 is a side elevation of my improved attachment showing the same attached to the bed rail.

Figure 3 is a vertical section taken on the line 3—3 of Figure 2 looking in the direction

of the arrows illustrating the novel formation of clamp.

Figure 4 is a horizontal section through the clamp taken on the line 4—4 of Figure 2 looking in the direction of the arrows.

Figure 5 is a detail perspective view showing the various parts of the clamp and tray in their disconnected positions.

Referring to the drawings in detail, wherein similar reference characters designate corresponding parts throughout the several views, the letter A generally indicates my improved device and B a hospital bed with which the same can be associated.

The hospital bed B can be of any preferred or ordinary character and only a sufficient portion of the same has been shown to illustrate the use of my improved device. As shown, the hospital bed B includes the longitudinally extending bed rail 10, which may be of channel bar construction.

My improved device A comprises a tray 15 and a novel clamp 30 for engaging the rail 10.

The tray 15 may include a wire mesh body 16 reinforced by an upper rectangular wire frame 17 which can be formed from a single bar of metal of the desired gage. As shown, one end of the frame of the tray 15 is extended to form a laterally extending arm 18, and the terminal of this arm is bent downwardly in a vertical plane to provide a pivot or hinge pin 19.

The clamp and support 30 comprises a main body section 31, formed from a single blank of sheet metal of the desired gage and this body plate section 31 includes an upper substantially U-shaped portion 32 and a depending triangular supporting plate 33. The upper U-shaped portion 32 is adapted to be slipped over the bed rail 10 into intimate contact therewith, while the supporting plate 33 depends therefrom. The upper edge of the U-shaped portion has formed thereon pins or guide barrels 34, for a purpose which will be later described. Likewise one edge of the supporting plate 33 has formed thereon hinge barrels 35. The opposite edge of the supporting plate 31 is provided with a bent back retaining flange 36. The clamp 30 also

includes a flat lock plate section 37, which is entirely independent of the body plate section 31. As shown, the upper edge of the lock plate 32 is provided on its upper edge and on one side edge with spaced guides or hinge barrels 38 and 39 respectively.

As stated, the body plate section is adapted to be slipped over the bed rail at the desired location thereon after which the lock plate section 37 is slipped in between the flange 36 and the supporting plate 33 and the same is then swung toward said supporting plate, with the upper guide barrel 38 in alignment or registration with the upper guide barrel 34 on the main plate. The hinge barrels 39 are likewise brought into alignment or registration with the hinge barrels 35. This closes the U-shaped portion 32 and prevents disengagement of the clamp and support from off of said rail. A lock pin 40 is placed through the registering guide barrels 34 and 38 to hold the sections 31 and 37 in their assembled positions on the bed rail, and the depending pivot pin or arm is slipped into the registering hinge barrels 35 and 39. This permits the convenient association of the tray with the bed and the tray can be swung on the hinge barrels 35 and 39 either under the bed or to one side of the bed laterally thereof.

In order to permit the convenient swinging of the tray to its operative or inoperative position the reinforcing frame 17 thereof is provided with an upstanding manipulating handle or rod 41 at a point spaced from the pivot pin 19 and this handle or manipulating rod 41 is of such a height as to extend above the bed rail whereby the same can be conveniently reached by the patient.

The tray is of a convenient size to receive both a urinal and a bed pan and it is obvious that when the tray is swung laterally of the bed the patient may conveniently reach either one of the same.

Changes in details may be made without departing from the spirit or the scope of this invention:—

What I claim is:

1. An attachment for hospital and like beds comprising a tray, a hinge pin carried by the tray, a two-part clamp and support for the tray comprising a main body part and lock plate part, the main body part having a substantially U-shaped portion for receiving the rail of the bed, aligned hinge barrels formed on the side edges of the main body part and the lock plate part and on the upper edges thereof, a lock pin extending through the aligned barrels on the upper edges of said parts, and the hinge barrels on the side edges of said part rotatably receiving the hinge pin.

2. An attachment for hospital beds comprising a bed pan and urinal receiving tray including a laterally extending arm project-

ing from one corner of the tray, a depending hinge pin on said arm, a bed rail clamp including a main body section having a U-shaped portion engaging about the bed rail, and a lock flange on one edge thereof, a lock plate section for abutting engagement with the body plate section and for closing the upper part of the U-shaped part, aligned hinge barrels formed respectively on the upper edges of the body section and the lock plate section and on the side edges thereof, the lock plate section having one edge received between the body plate section and the flange, and a lock pin extending through the aligned hinge barrels on the upper edges of the main body section and the lock plate section, the other barrels receiving the hinge pin, and manipulating handles carried by the tray in spaced relation to the hinge pin.

In testimony whereof I affix my signature: 85
BIRDIE O. HORNER.
